(57) CLAIM

I claim the ornamental design for a nite stand, as shown and described.

DESCRIPTION

FIG. 1 is a left front perspective view of a nite stand showing my new design;

FIG. 2 is a front perspective view thereof;

FIG. 3 is a right front perspective view thereof;

FIG. 4 is a top perspective view thereof; and,

FIG. 5 is a left side perspective view thereof, the opposite side being a mirror image thereof.

1 Claim, 5 Drawing Sheets
